UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,305,548.

Specification of Letters Patent. Patented June 3, 1919.

Application filed July 15, 1916. Serial No. 109,450.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention has reference to typographical machines, such as linotype machines of the general organization represented in Letters Patent of the United States to O. Mergenthaler, No. 436,532, wherein matrices representing the various characters to appear in print are stored in a channeled magazine and are released therefrom one at a time through the action of escapement devices controlled by finger keys. In these 15 machines, it is common to store the more frequently used characters, such as the letter *e*, in two or more channels of the magazine, and to provide mechanism whereby a single finger key may effect their release from the 20 different channels in alternation or succession. My present invention is directed to this same general result, and is intended to simplify the mechanism and to render it more certain in operation, as will be more 25 fully pointed out in the detailed description to follow.

In the accompanying drawing, I have shown my invention merely in preferred form and by way of example and as applied 30 to the particular style of machine mentioned, but obviously many variations and alterations may be made therein, and in its mode of application, which will still be comprised within its spirit. Thus it may be applied 35 to other forms of escapement or matrix releasing devices and to other styles of machines, such as typesetters and the like. Generally speaking, I desire it to be understood that I do not limit myself to any specific form or embodiment, except in so far 40 as such limitations are specified in the claims.

Referring to the drawing:

Figure 1 is a perspective view, partly in 45 section, of the escapement actuating mechanism of a linotype machine with my invention applied thereto;

Fig. 2 is a side elevation of my improved devices; and

Figs. 3 and 4 are sectional details showing 55 the parts in different relative positions.

The matrices X are stored in the channeled magazine A and are released therefrom by the escapements B, one for each channel of the magazine, and which are 60 actuated by a series of vertical reeds, the two shown, C¹ and C², being the outermost ones of the series and alone concerned with the present invention. These two reeds are 65 operated by the reciprocating member C, which is controlled in its reciprocations by the pivoted yoke D, the lifting cam or eccentric D¹, the constantly rotating roll D², the yoke sustaining dog D³, the vertical slide D⁴, and the finger key D⁵. The parts so far 70 described are of the usual construction and are described in the U. S. Patent to Mergenthaler, No. 658740.

My invention is directed to the provision of a simplified form of mechanism for shifting the reciprocating member C laterally periodically so that it may actuate the two escapement reeds C¹ and C² alternately or successively. In the present instance, this shifting is controlled automatically by the 75 actuating member or its finger key, and so as to take place when said key has been actuated a certain definite number of times. The member C is slidably arranged as usual in the guide plates E and C⁴, the former according to my invention being attached to the inner end of a short cylindrical stud or plunger E¹ arranged to slide endwise in the framework to locate the member C beneath either one of the overlying escapement reeds 80 C¹, C². A key or pin E³ engaging in an elongated slot in the stud serves to hold it against rotation and to limit its movements in opposite directions. At its outer end, the stud is formed with a head portion E⁵, 85 against which bears a spring E⁴ reacting against the framework and tending constantly to shift the stud to the left to locate the actuating member in operative relation to the outer escapement reed C¹. This tendency of the spring, however, is controlled by a rotary face cam F loosely surrounding the stud E¹ and having extended depressed and raised portions arranged to coöperate with a laterally projecting pin E² thereon, so as 90 to shift the actuating member to the right or left, as the case may be.

The cam F is rotated by means of an at-

tached ratchet wheel F^1 , held against retrograde movement by an overlying detent F^2 , and which is advanced tooth by tooth by a pawl H^2 pivoted to a projecting portion of a ring shaped rocker plate H loosely surrounding the hub portion of the cam. The rocker plate is formed with a laterally projecting stud H^1 seated in a forked arm C^3 fixed to and projecting laterally from the 10 actuating member C , which thus controls the rocking movements of the plate. A spring H^3 , connected at one end to the outer arm of the pawl H^2 and pulling from a fixed part of the machine, serves to hold the pawl 15 in engagement with the ratchet wheel and to advance the latter when permitted by the actuating member.

The action of the parts will now be clear. Upon each actuation of the finger key D^5 , 20 the member C is raised to actuate one of the escapements, and through its connections with the rocker plate H shifts the latter upwardly therewith against the action of the spring H^3 and locates the pawl H^2 in engagement with a higher tooth on the ratchet wheel F^1 . Then upon the descent of the actuating member, the spring, by pulling downwardly on the pawl, restores the parts to their original position and at the same time 25 causes the pawl to advance the ratchet wheel the distance of one tooth. This progressive advance of the ratchet wheel effects the corresponding rotation of the cam F and brings its raised and depressed surfaces successively 30 into engagement with the laterally projecting pin E^2 on the sliding spring-pressed plunger E^1 , which is thus caused to shift the actuating member C into operative relation first to one and then to the other of the 35 escapement reeds C^1 and C^2 alternately. Thus, as shown in Figs. 1, 2 and 3, the raised surface of the cam is active, holding the member C to the right beneath the reed C^2 against the action of the spring E^4 , which 40 tends constantly to move the member to the left. This condition persists until the depressed portion of the cam is brought into engagement with the pin E^2 by the continued rotation of the ratchet wheel F^1 , at 45 which time (see Fig. 4) the spring E^4 is permitted to shift the member C to the left into operative relation to the escapement reed C^1 , the parts remaining in this position until the raised surface of the cam is brought 50 into action by the further rotation of the ratchet wheel.

As shown in the drawing, the extent of the cam surfaces is such that the shifting of the actuating member C back and forth is 55 effected only after a plurality of actuations of said member or its finger key, so that say six matrices may be drawn from each of the two magazine channels alternately. It is obvious, however, that by altering the 60 extent of the cam surfaces of the number of

the teeth on the ratchet, matrices may be drawn from the channels in various quantities, and, if desired, in unequal quantities, as for instance five from one and seven from the other. 70

It will be seen that my improved mechanism comprises parts which are few in number and of simple construction and efficient in operation, and which may be easily applied to existing machines without material 75 alteration therein. In addition, the shifting mechanism, being controlled by the power-actuated member C , is positive and certain in action. The relative proportioning of the parts is also advantageous in that 80 definite quantities of matrices are released from the two magazine channels at the required intervals and without putting the devices through an unnecessary number of shifting operations. 85

As previously stated, I have shown my invention merely in preferred form and by way of example, and obviously many changes and modifications therein will suggest themselves to those skilled in the art without departure from its scope. 90

Having thus described my invention, its construction and mode of operation, what I claim and desire to secure by Letters Patent of the United States, is as follows: 95

1. In a typographical machine, the combination of a plurality of matrix releasing escapements, a single actuating device therefor, a shifting guide wherein the actuating device is slidably arranged, a sliding plunger 100 carrying said guide, a face cam loosely surrounding the sliding plunger and controlling its movements in opposite directions, and means for rotating the cam periodically. 105

2. In a typographical machine, the combination of a plurality of matrix releasing escapements, a single actuating device therefor, a shifting guide wherein the actuating device is slidably arranged, a sliding plunger carrying said guide, a face cam loosely surrounding the sliding plunger and controlling its movements in opposite directions, and means operated by the escapement actuating device for rotating the cam periodically. 110

3. In a typographical machine, the combination of a plurality of matrix releasing escapements, a single actuating device therefor, a shifting guide wherein the actuating device is slidably arranged, a sliding plunger 120 carrying said guide, a face cam loosely surrounding the sliding plunger and controlling its movements in opposite directions, and means operated by the escapement actuating device for rotating the cam periodically, the said cam being formed and arranged so as to alter the position of the actuating device after given pluralities of actuations thereof. 125

4. In a typographical machine, the combi- 130

nation of the two escapement reeds C¹ and C², the single actuating device C therefor, the shifting guide E wherein the actuating device C is slidably arranged, the sliding 5 spring-pressed plunger E¹ carrying the guide E and formed with the laterally projecting pin E², the face cam F loosely surrounding the plunger and having raised and depressed portions arranged to engage the 10 pin, and means for rotating the cam periodically.

5. In a typographical machine, the combination of a plurality of matrix releasing escapements, a single actuating device therefor, a shifting guide wherein the actuating device is slidably arranged, a sliding plunger carrying said guide, a face cam loosely surrounding the plunger and controlling its movements in opposite directions, a ratchet 15 wheel fixed to the cam, and a reciprocating pawl coöperating with the ratchet wheel to rotate the cam periodically.

6. In a typographical machine, the combination of a plurality of matrix releasing 20 escapements, a single actuating device therefor, a shifting guide wherein the actuating device is slidably arranged, a sliding plunger carrying said guide, a face cam loosely surrounding the plunger and controlling its 25 movements in opposite directions, a ratchet wheel fixed to the cam, and a reciprocating pawl engaged with the ratchet wheel and operated by the shiftable actuating device for 30 rotating the cam periodically.

35 7. In a typographical machine, the combination of a plurality of matrix releasing escapements, a single actuating device therefor, a shifting guide wherein the actuating device is slidably arranged, a sliding plunger 40 carrying said guide, a face cam loosely surrounding the plunger and controlling its movements in opposite directions, a ratchet wheel fixed to the cam, a rocker plate provided with an actuating pawl for the ratchet 45 wheel, and means for moving the plate in opposite directions.

8. In a typographical machine, the combination of a plurality of matrix releasing escapements, a single actuating device therefor, a shifting guide wherein the actuating device is slidably arranged, a sliding plunger carrying said guide, a face cam loosely surrounding the plunger and controlling its movements in opposite directions, a ratchet 50 wheel fixed to the cam, a rocker plate provided with an actuating pawl for the ratchet wheel, a connection through which the upward movement of the actuating device effects the idle movement of the rocker plate,

and a spring for effecting the active or 60 ratchet advancing movement of the plate as the actuating device descends.

9. In a typographical machine, the combination of a plurality of matrix releasing escapements, a single actuating device therefor, a shifting guide wherein the actuating device is slidably arranged, a sliding plunger carrying said guide, a face cam loosely surrounding the plunger and controlling its 65 movements in opposite directions, a ratchet wheel fixed to the cam, a rocker plate provided with an actuating pawl for the ratchet wheel and connected to the escapement actuating device, and a spring also connected to the actuating pawl and serving to hold it 70 in engagement with the ratchet wheel and to rotate the latter when permitted by the actuating device.

10. In a typographical machine, the combination of a plurality of matrix releasing 75 escapements, a single actuating device therefor, a shifting guide wherein the actuating device is slidably arranged, a sliding plunger carrying said guide, a face cam loosely surrounding the plunger and controlling its 80 movements in opposite directions, a ratchet wheel fixed to the cam, a rocker plate provided with an actuating pawl for the ratchet wheel and connected to the escapement actuating device, a spring also connected to 85 the actuating pawl and serving to hold it in engagement with the ratchet wheel and to rotate the latter when permitted by the actuating device, and a stationary 90 detent to prevent retrograde movement of the ratchet 95 wheel.

11. In a typographical machine, the combination of the escapement reeds C¹ and C², the single actuating device C therefor, the shifting guide E wherein the actuating device is slidably arranged, the sliding spring-pressed plunger E¹ carrying the guide and provided with the laterally projecting pin E², the face cam F loosely surrounding the plunger E¹ and provided with the ratchet 100 wheel F¹, the rocker plate H loosely surrounding the cam F and carrying the pivoted actuating pawl H² and formed with the laterally projecting stud H¹, the spring H³ attached to the outer arm of the pawl H² 105 and pulling from a fixed part of the machine, and the arm C³ fixed to the actuating device C and connected to the pin H¹, the said parts operating substantially in the manner shown and described.

In testimony whereof, I have affixed my signature.

DAVID S. KENNEDY.
